(57) **CLAIM**

The ornamental design for a woodturning tool, as shown and described.

DESCRIPTION

FIG. 1 is a top, isometric perspective view of a woodturning tool in accordance with our design;

FIG. 2 is a bottom isometric perspective view of the woodturning tool of FIG. 1;

FIG. 3 is a front end elevation view of the woodturning tool of FIG. 1;

FIG. 4 is a rear end elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is a cross-section through line 9-9 of FIG. 8.

The broken lines illustrate portions of the woodturning tool which form no part of the claimed design.

The dot-dash broken lines shown in the drawings indicate section lines for detailed cross-section views and form no part of the claimed design.
